UNITED STATES PATENT OFFICE.

ROBERT C. TAFT, OF MOLINE, ILLINOIS.

CAR-UNDERFRAME.

1,340,576.

Specification of Letters Patent. Patented May 18, 1920.

Application filed June 19, 1919. Serial No. 305,398.

To all whom it may concern:

Be it known that I, ROBERT C. TAFT, a citizen of the United States, residing at Moline, in the county of Rock Island and State 5 of Illinois, have invented new and useful Improvements in Car - Underframes, of which the following is a full, clear, and exact description.

My invention relates to improvements in 10 underframes of cars, and particularly to the construction thereof at the intersection of the body-bolster and draft members or center-sills.

The object of my invention is to provide 15 a continuous construction particularly of the backbone of a car, that is, through the body-bolster in the longitudinal line of the draft members and center-sills, so as not to detract from the strength and ability of the 20 underframe to transmit the heavy pulling and buffing strains to which the car is subject, and a further object is to fill in the space between the body-bolster and the adjacent ends of the sub-sills, and the bolster 25 and the rear ends of the draft-members, substantially as hereinafter fully described and pointed out in the drawings.

In the drawings:

Figure 1 is a side elevation of the portion 30 of the underframe of a railway car adjacent to the inner section of the draft-sills and center-sills at the intersection of the bolster having my improvements applied thereto.

Fig. 2 is a transverse section thereof taken 35 on dotted line 2, 2, Fig. 1, looking in the direction indicated by the arrows.

Fig. 3 is a transverse section taken on dotted line 3, 3, Fig. 1, looking in the direction indicated by the arrows.

Fig. 4 is a view similar to that shown in 40 Fig. 1 and disclosing a modified construction of my invention.

Fig. 5 is a transverse section of said modified construction taken on dotted line 5, 5, 45 Fig. 4.

Fig. 6 is a similar transverse section taken on dotted line 6, 6, Fig. 4.

In the drawings A represents the center-sills of the underframe of car, which are 50 designed to extend from end to end of the same; 6 the flooring supported above and upon said center-sills, and 7, a transverse metal I-beam bolster extending from side to side of the car below said sills. The center-sills consist preferably, of wooden beams, 55 the outer and under sides of each of which

are, particularly in the vicinity of the bolsters, reinforced and strengthened by a metal reinforcing plate, B, that is L-shaped in cross-section.

Draft-members 8 are secured in any suitable manner to the under sides of the center sills in front of the bolster, and sub-sills 12 are secured to the under sides of said center-sills at the rear of the bolster, but there is a 60 space left between the rear ends of said draft members and the bolster and the adjacent ends of said sub-sills and said bolster.

It is the principal object of my invention to fill in the space between the ends of the 65 draft members and the bolster and the ends of the sub-sills and the bolster. This I accomplish by means of cast metal blocks 13, which are interposed between the draft members and the bolster, and blocks 18, 70 which are inserted between the sub-sills and the bolster. The edges of these blocks are flanged. The forward vertical edges of blocks 13 are secured to the adjacent ends 75 of the draft members by means of angle 75 irons 15, one flange of which being riveted to the flange of the block and the other flange to the web of the draft members, substantially as shown. The rear portion of the upper edges of these blocks 13 are rabbeted 80 to form seat 5 for the flanges of the bolster. The depth of blocks 13 is such that their 85 upper edges bear against the under side of the horizontal portion of the reinforcing plates 7, and the lower edges thereof are in 90 a horizontal plane slightly below the horizontal plane of the lower flanges of the draft-sills and said lower edges are provided with a forward extension or lug 14, which is 95 riveted to the lower flange of the draft-sill. 95 The rear portion of the said lower edges are rabbeted to form seat 5 for the lower flanges of the bolster.

The depth of the draft members in front 100 of the bolster is preferably greater than that of the sub-sills at the rear thereof. The cast metal blocks 18, hereinbefore referred to, substantially corresponds to block 13. The upper edge of each block 18, is similarly rabbeted to provide seat 5, for the 105 upper rearwardly projecting flange of the bolster, and near its lower edge said block 18, has a lug 19, projecting rearwardly therefrom which laps against the under side of the forward end of the sub-sill substantially as shown.

In Fig. 4 of the drawings I show a

slightly modified construction of my invention. In this modification each draft member 25 and the superposed reinforcing plate 22 are cast in one piece of metal. The rear 5 ends of the draft members terminate in the same relative point as the draft members in the preferred form of my invention, but the integral reinforcing plates 22 arch over and extend to the rear of the bolster and form 10 inverted sockets or seats for the adjacent ends of the sub-sills. This modification employs blocks 17 and 20, which are the counterparts of blocks 13 and 18 of the preferred form of my invention, excepting that 15 the forward portion of the under edges of the blocks 20, are rabbeted to accommodate and provide seats for the rear lower flange of the bolster.

In both the preferred and modified forms 20 above described, a bolt 30 extends through the rearwardly projecting lug of the blocks 18 and 20 which extends up to and has its head countersunk in the flooring of the car, and in both of said construction bolts 31 and 25 32 extend down from the floor in which their heads are countersunk through the upper flanges of the bolster and the flanges of 30 the upper rabbeted edges of both blocks 13, and 18, in the preferred form and blocks 20 of the modified form of my invention.

I do not wish to be confined to the exact 35 shape or dimensions of the blocks hereinbefore described, as it is obvious they may be changed to suit the changed design of the underframe in connection with which they 40 may be used, and said blocks may be used in connection with underframes in which the draft rigging is directly attached to the center-sills, or attached to draft members secured to and placed below said center-sills.

What I claim as new is:

1. In an underframe for cars the combination with the body-bolsters and draft-members the rear ends of which do not come 45 in contact with said bolsters, of blocks interposed between said draft-members and said bolsters, said body-bolster, blocks and draft-members being permanently attached 50 to each other so that the strain upon the draft-members will be continuous from end to end of the car.

2. In an underframe for cars the combination with the body-bolsters and central 55 longitudinal disposed sills that extend between said bolsters, but do not come in direct contact therewith, of blocks interposed between the ends of said sills and said bolsters, said sills and bolster being permanently attached to each other through the 60 medium of said blocks.

3. In an underframe for cars the combination with the body-bolsters, draft-members the rear ends of which do not come 65 in contact with said bolsters, and central

longitudinally disposed sills that extend between said bolsters but do not contact therewith, of blocks interposed between the said ends of said draft-members and bolsters and the adjacent ends of sills and said bolsters, said draft-members, body-bolsters, 70 sills and blocks being permanently attached to each other so as to transmit the pulling and buffing strains through said blocks continuously from end to end of the car. 7

4. In an underframe for cars the combination with the body-bolsters and draft-members the rear ends of which do not come in contact with said bolsters, of blocks which 80 are flanged to receive the body bolsters and the sills and which are interposed between said draft-members and said bolster.

5. In an underframe for cars the combination with the body-bolsters and draft-members the rear ends of which do not come 85 in contact with said bolsters of blocks interposed between said draft-members and said bolster and having one of its horizontal edges rabbeted to provide a seat for one of the flanges of the bolster. 90

6. In an underframe for cars the combination with the body-bolsters, and central longitudinal disposed sills that extend between said bolsters, but do not come in direct contact therewith, of blocks interposed 95 between the ends of said sills and said bolsters and having one of its horizontal edges rabbeted to provide a seat for one of the flanges of the bolster.

7. In an underframe for cars the combination with the body-bolsters and draft-members the rear ends of which do not come 100 in contact with said bolsters of blocks interposed between said draft-members and said bolster and having the rear portion of its 105 horizontal edges rabbeted to accommodate and provide seats for the flanges of the bolster.

8. In an underframe for cars the combination with the body-bolsters and draft-members the rear ends of which do not come 110 in contact with said bolsters, of blocks interposed between said draft-members and said bolster and having a lug projecting forward from their lower forward corners that lap under and are secured to the rear ends of the draft-members. 115

9. In an underframe for cars the combination with the body-bolsters and central longitudinal disposed sills that extend between said bolsters, but do not come in direct contact therewith, of blocks interposed between the ends of said sills and said bolsters, and having a lug projecting rearward from their lower rear corners that lap 120 under and are secured to the near ends of the sills.

10. In an underframe for cars the combination with the body-bolsters and draft-members the rear ends of which do not come 130

in contact with said bolsters, of blocks interposed in and conforming in outline to the space between said draft-members and said bolster and having a lug projecting forward 5 from their lower forward corners that laps under and is secured to the rear ends of the draft members.

11. In an underframe for cars the combination with the body-bolsters and central 10 longitudinal disposed sills that extend between said bolsters, but do not come in direct contact therewith, of blocks interposed in and conforming in outline to the space between the ends of said sills and said 15 bolsters and having a lug projecting rearward from their lower rear corners that lap under and are secured to the near ends of the sills.

12. In an underframe for cars the combination with the body-bolsters, draft-mem- 20

bers the rear ends of which do not come in contact with said bolster, and central longitudinally disposed sills that extend between said bolsters but do not contact therewith, of blocks that conform in outline to and are 25 interposed in the spaces between the said ends of said draft-members and bolsters and the adjacent ends of sills and said bolsters, said blocks having lugs projecting from the lower corners thereof farthest from said 30 bolsters that extend under and are secured to said draft-members and sills respectively.

In witness whereof, I have hereunto set my hand this 16th day of June, 1919.

ROBERT C. TAFT.
